UNITED STATES PATENT OFFICE.

JOHN L. KEEL, OF ROSWELL, NEW MEXICO.

REFRIGERATOR.

1,210,172.

Specification of Letters Patent. Patented Dec. 26, 1916.

Application filed March 1, 1915. Serial No. 11,359.

To all whom it may concern:

Be it known that I, JOHN L. KEEL, a citizen of the United States, residing at Roswell, in the county of Chaves and State of New Mexico, have invented certain new and useful Improvements in Refrigerators, of which the following is a specification, reference being had to the accompanying drawings.

10 This invention relates to certain improvements in refrigerators, and has for its primary object to provide means for thoroughly ventilating the interior of the refrigerator and maintaining the same at a minimum temperature in winter without the use of ice or other refrigerating mediums.

15 The invention has for its particular object to provide a refrigerator having the usual door in its front wall, and means provided in said door for permitting the free circulation of air through the interior of the refrigerator, such communicating means between the interior of the refrigerator and the atmosphere being closed during the summer when ice is used, to prevent the escape of the cold air.

20 It is an additional object of my invention to provide a refrigerator of the above character which is exceedingly simple in its construction, may be easily maintained in a thoroughly sanitary condition, and can be produced at comparatively small manufacturing cost.

25 With the above and other objects in view, my invention consists in the novel construction, combination and arrangement of parts to be hereinafter more fully described, claimed and illustrated in the accompanying drawing, in which—

30 Figure 1 is a perspective view of a refrigerator constructed in accordance with the present invention, and Fig. 2 is an enlarged detail section through the refrigerator door.

35 Referring in detail to the drawing, 1 designates the body of the refrigerator, which is of any approved form or construction, the walls thereof being provided with any preferred insulating means. The refrigerator is of course provided with the usual ice compartment indicated at 2, and the provision compartment 3. This latter compartment is closed by means of a hinged door 4.

40 As clearly shown in Fig. 2 of the drawing, the door 4 is provided with a central

5 circular opening 5 therethrough in which a cylindrical metal sleeve or tube 6 is arranged, the inner end of said sleeve being provided with an outwardly projecting annular flange 7 for engagement against the inner face of the door around the opening 5 therein. The outer end of the metal sleeve is formed with an outturned annular bead 8, for a purpose to be later referred to. 60 Within the sleeve 6 and adjacent the outer end thereof, a partition 9 of wire gauze or other reticulated material is arranged, and suitably secured to the wall of said sleeve. This perforate partition wall effectually excludes foreign matter or insects from the interior of the refrigerator, but admits of the free entrance of air thereto. Thus, during the winter months, when the atmospheric temperature is sufficiently low to 70 obviate the necessity of providing an artificial refrigerating medium, cold air may freely enter the provision compartment through the sleeve 6 so that the temperature thereof will be at all times substantially the 75 same as the atmospheric temperature whereby the contents of said compartment are preserved against spoiling.

During the summer months, the compartment 2 is of course kept supplied with ice, 80 and this compartment is closed by means of a suitable lid or cover 10. The outer open end of the sleeve 6 is also closed by a removable cap 11 which is provided with an annular flange for frictional engagement with 85 the bead 8 on the outer end of said sleeve. The cold air is thus retained in the provision compartment of the refrigerator.

90 In the provision chamber suitable perforated shelves 12 are arranged to support the foodstuffs. These shelves are preferably formed of aluminum and the walls of the provision compartment 3 are preferably lined with the same material.

95 From the foregoing description, taken in connection with the accompanying drawing, the construction, manner of operation, and several advantages of my improved refrigerator will be clearly and fully understood. The invention, while exceedingly simple in 100 its construction, is nevertheless highly convenient, serviceable and practical in use, as it admits of the proper preservation of large quantities of foodstuffs during the winter months without the necessity of using a 105 refrigerating medium. It is obvious that the air passage afforded by the provision 110

of the sleeve 6 in the door of the refrigerator may be of any desired diameter in accordance with the size and capacity of the refrigerator.

5 The invention is also susceptible of considerable modification in the form, proportion and arrangement of the several structural features thereof, and I therefore reserve the privilege of resorting to all such 10 legitimate changes as may be fairly embodied within the spirit and scope of the invention as claimed.

Having described my invention, what I claim is:

15 In a ventilating device for refrigerators, the combination with a refrigerator having a provision compartment and a hinged door therefor provided with a central opening; of a metal sleeve extending through said

opening and permanently fixed therein, said sleeve being provided upon its outer end with an outturned bead engaging the face of the door, a wall of reticulated material permanently secured within the sleeve in spaced relation to its outer end, and an imperforate closure cap having an annular flange for frictional engagement upon said bead, said cap completely closing the outer end of the sleeve and cutting off communication between the provision chamber and the atmosphere.

In testimony whereof I hereunto affix my signature in the presence of two witnesses.

J. L. KEEL.
